SWITCH

Rudolf Popp, Valparaiso, Ind., assignor to McGill Manufacturing Company, Valparaiso, Ind., a corporation of Indiana

Application August 24, 1935, Serial No. 37,657

3 Claims. (Cl. 200—168)

My invention relates in general to electrical switches and, more in particular, to an improvement over the structure of my Patent #1,996,030, in a small, compact and inexpensive pull-chain switch.

In present-day competition in the electrical switch art, low-priced, high quality merchandise is essential to a successful business. The more complicated, multi-part switch of the prior art is in many instances becoming obsolete because of a high cost price with a consequent high selling price. However, very definite limitations are put on low cost devices by very rigid underwriters' requirements. New fixture designs, and general switch requirements necessitate a small, compact structure.

It is an object of my invention to provide a simplified, improved electrical switch.

A further object is to provide an electrical switch simple and sturdy in construction, and meeting all of the underwriters' requirements.

A still further object is to provide a switch with a very small number of parts to in turn reduce manufacturing and assembly costs to the lowest possible figure.

It is also an object of my invention to provide a switch which is positive in operation and capable of long, continued use.

One of the features of my invention is an improved stationary contact and conductor terminal member.

Another feature is a one-piece simplified, molded actuator for actuating the contact mechanism.

A still further feature is a sturdy, low cost combination mounting frame and nipple removably carried in the switch housing.

Other objects and features of my invention will be apparent from the following description taken with the drawing, in which:

Fig. 1 is a perspective view of my switch slightly larger than the actual size thereof.

Fig. 2 is an enlarged plan view with the cover of the switch removed.

Fig. 3 is a sectional view along the line 3—3 of Fig. 5.

Fig. 4 is a cross-sectional view along the line 4—4 of Fig. 3.

Fig. 5 is an irregular section along the line 5—5 of Fig. 3.

Fig. 6 is an enlarged perspective view of the stationary contact of my invention.

Fig. 7 is a perspective view of the rotatable bridging contact member.

Fig. 8 is an enlarged perspective view of the actuator.

In practicing my invention, I provide a one-piece molded insulating housing with a removable insulating cover, a cavity opening from one face of said housing for carrying a switch mechanism on a mounting post in the center of said cavity and integral with the housing. The switch mechanism comprises a bridging contact member centered on the post, a one-piece actuator for rotating said bridging contact member, and removable stationary contacts mounted in depressions on each side of the cavity in said housing. The stationary contact members are of a relatively soft metal comprising a contact portion lying in the cavity, an offset connecting portion and a terminal portion with a plurality of punched, staggered holes, with said portion folded over to pinch and hold a wire conductor in cooperation with the staggered, punched holes. A combination threaded nipple and mounting nut is removably carried in said housing cooperating to carry the cover as well as provide threadable extension means for mounting the switch on a fixture. A pull chain is carried on the actuating member and extends through the nipple for operating the switch.

Referring now to the drawing, I provide a one-piece insulating housing 10 of any suitable molded material, but preferably of a material commercially known as "Bakelite", substantially rectangular in shape except for a projecting portion 11 extending from one side at one corner thereof to carry a switch mounting frame or nut therein. The neck or projecting portion 11 comprises a cavity 12 with offset recesses 13 forwardly and at each side thereof and a corresponding open slot 14 at the bottom. The cavity extends forwardly from the recesses to an integral segmental collar 16, shown particularly in Figs. 2 and 3.

A projection 17 at the rear of the housing is apertured to receive a mounting eyelet 18 in an insulating cover 19, as shown in Figs. 1 to 5. A mounting frame or nut 21 formed with a forwardly-extending threaded bearing surface 22 is mounted with an ear 23 extending into slot 14 and an ear 24 fitting into a corresponding slot 26 in the cover 19, with both ears extending from a vertical flange on the nut. A nipple 25 with a knurled flange at one end, and an elongated threaded outside surface extending rearwardly therefrom is threadably carried in the nut 21. Both the nipple and mounting nut may be inexpensive screw machine parts, or the nut 21 may be formed in an extrusion process.

As to the switch mechanism, this rotates on a post 27 integral with the housing 10, and extends

ing upwardly in the center of an enlarged cavity 28 within said housing. The switch mechanism comprises a one-piece bridging contact member 29 (Fig. 7) formed preferably from a phosphor bronze spring material and is mounted to rotate on the floor of the cavity 28 between a pair of stationary contacts 31 and 32, as will be hereinafter explained. The bridging contact member includes a pair of resilient contacting blades 33 oppositely disposed and standing upwardly from a center ring portion 34. The ring is split transversely, at one side, as at 36, with an upturned tongue 37 to act as a pawl.

A one-piece actuating member or actuator 38 is provided for operating the bridging contact member 29.

The actuator 38 is preferably molded, and from insulating material. From the standpoint of the cost of the mold and ease of handling the 20 molded article, it is important to have vertical, straight side walls and no portions projecting outwardly from the body. These requirements are satisfied in the actuator with a center core for fitting over the post 27, and a segmental shoulder 25 39 therein for riding on an annular collar 41 integral with the post at the base thereof. A stop or key 42 on the post engages the ends of the shoulder 39 to limit the movement of the actuator. The bottom portion of the actuator is provided with a plurality of longitudinally-projecting ratchet teeth 43 for successively engaging the tongue 37 of the bridging contact member.

An annular flange 44 of the same diameter as the cavity 28 of the housing is provided on the 35 actuator to ride on the ledge 46 at the bottom of the cavity formed in providing alternate ledges and ratchet tooth-like recesses 47 for the bridging contact member and stationary contacts, as will be hereinafter described. The upper face of the 40 flange is adapted to carry a pull chain 48, with the first link 48' lying in a depression 49, and retained therein by the integral stud 51 forming a narrow slit 52. In order that the chain may lay more regularly around the wall 53 of the core of 45 the actuator, slight depressions are formed therein adjacent the slit 52, as shown in Fig. 8.

A coiled retrieving spring 54 is carried loosely in the actuator and around the post 27. One end is turned inwardly and projects into a slot 50 56 across the top of the center post. The other end of the spring is turned outwardly and engages against a shoulder 57 of a comparatively wide recess in the wall 53 of the actuator. The spring is given approximately one half turn to tension it before the inwardly-extending end is 55 pressed into the slot 56.

As to the stationary contact members, it has been customary in the art to provide a combination contact and terminal, with a screw post 60 threaded into a terminal strip. The terminal portion is also formed to carry a conductor with the latter soldered therein. Both constructions are expensive in material and in labor, in the original and final assembly thereof. I provide a 65 very simple, yet effective, combination contact and terminal in the members 31 and 32 formed in one piece from a relatively soft metal plate. Both members are alike, except that they are mounted oppositely in the housing, and for convenience I 70 will simply describe member 31, as illustrated in Fig. 6.

This member is stamped out with an arcuated contact blade 58 connected with a terminal portion 59 through a constricted neck portion 61. In 75 stamping the terminal portion, a plurality of

holes 62 are stamped out, to subsequently lie on opposite legs or walls of the terminal, and staggered longitudinally so that preferably no two holes will lie opposite one another. The holes are stamped in such a manner that the usual burr which results from the stamping will lie on the outside of the formed terminal. The member 31 is finally formed so that the terminal portion is doubled over, as shown in Fig. 6, to pinch the uncovered end of a conductor 63 and positively 10 retain the same by frictional engagement between the walls and the wire, and also by virtue of the fact that, when the walls are punched together, the wire is forced slightly into the holes 62. In the commercial embodiment of my invention, this construction has acted to positively retain the wire without any additional holding means, such as soldering, as has always been necessary in the prior art.

The members 31 and 32 with the conductors 20 63 fastened therein are mounted in corresponding recesses in opposite sides of the housing, as shown particularly in Figs. 3 and 4. This mounting is also shown in Fig. 2 with the insulation of the conductors 63 lying in channels 64 opening 25 into cavities 66 rectangular in shape and slightly deeper than the depth of the portion 59. The channels 64 are long enough so that the insulation on the wire extends into the housing far enough so that it will not pull out and leave the 30 wire bare. A channel 67 is also provided, opening into the cavity 28 of the housing on each side thereof to carry the neck portion 61. The contact blades 58 each abut a ratchet tooth in the bottom of the cavity 28, as shown in Fig. 3, and engage 35 against a shoulder of a recess 47 to hold the blade rigidly in position. The members 31 and 32 are retained in the housing as a result of the frictional engagement of the outer faces of the terminal portions 59 with the walls of the mounting 40 cavities 66. There is a slight resiliency in the metal which cooperates in this action, and more important, a cutting frictional engagement exists between the sharp burr on the holes 62 and the 45 walls of the cavity. This obviates the necessity of relying on the cover 19 to retain the members in the housing, as is the case in some prior art switches. This is a marked advantage in view of the fact that the covers sometimes warp slightly at their outer edge to bend away from the upper 50 face of the wall of the housing.

In assembling the switch, the members 31 and 32 are placed in their respective cavities. The bridging contact member 29 is slipped over the post 27 to the position shown in Fig. 3. The 55 actuator 38 is dropped into position and the retrieving spring 54 assembled as previously described. After this is accomplished, the chain 48 is mounted on the actuator and threaded through the nipple 25 in the usual manner. The mounting nut 21 is assembled in the neck of the housing to carry the nipple 25, and the cover is placed on the housing as shown in Fig. 5. As may be noted from this figure, the post 27 with the slot 56 extends upwardly flush with the top face of the 60 cover. In this manner the end of the spring is securely retained in the slot by means of the cover. The ears 23 and 24 on the flange of the mounting nut, together with the lower edge of the eyelet 18, are upset to rigidly retain the cover 65 in position.

The switch is positive in operation with the chain moving the actuator 38, limited in its movement by the segmental collar 39 and key or stud 42, to in turn operate the bridging contact mem- 70 75

ber 29. The ratchet teeth 43 of the actuator successively engage the tongue or pawl 37 of the bridging contact member. The nipple 25 may be readily removed and then threaded into the mounting nut 21 to quickly and firmly mount the switch as desired.

This mounting combination, as may be understood from a consideration of the drawing, is readily adapted to rather widely different mounting positions. With the somewhat elongated threaded portion on the nipple 25, and the threaded neck of the nut 21 extending to the mouth of the housing, the switch may be rigidly mounted on a wide or thick board, wall, or fixture, for it is necessary that only a few threads of the nipple be threaded into the nut. On the other hand, the nipple threads into the nut 21 so far that a paper may be firmly gripped between the knurled collar of the nipple and the mouth of the nut as shown in Figs. 3 and 5, thereby mounting the switch on the thinnest possible material. This construction has a further advantage in that with the knurled head of the mounting nipple 25 bearing against the mouth of the nut 21 rather than against the housing, any pressure may be applied to tighten the nipple without danger of the nut being pulled from the housing. This construction eliminates the necessity of a large number of different sized mounting elements, facilitates mounting, and thereby reduces installation costs in material and labor.

Although I have described and illustrated my invention in its preferred embodiment, it is understood that I am not limited thereby, but limit the invention only by the scope of the appended claims.

I claim:

1. In a switch, a substantially cup-shaped housing for carrying switching mechanism therein, with said housing having an aperture in a sidewall thereof, a cover for said switch originally pivotally secured at a sidewall opposite to said apertured sidewall, and combination means for mounting said switch and retaining said cover, said means comprising a one-piece flanged collar retained in said housing inwardly from the aperture in the sidewall with the collar extending into the aperture and having a flange extending

out of the housing and through an aperture in the cover to be upset on said cover to prevent pivotal movement thereof, and cooperating with the pivot securing means to prevent removal of said cover, and a mounting nut with an enlarged head and having a nipple portion in said collar and threadably adjustable in and out thereof to clampingly mount the switch.

2. In a switch for mounting on a panel or the like, a walled housing of insulating material having an integral extension on one sidewall and an aperture in the opposite sidewall thereof, a cover for the top of said housing secured to said housing at one side by securing means through said cover and said wall extension, and secured at the other side thereof by combination switch mounting and cover securing means, said means including a one-piece internally-threaded sleeve in the aperture of the sidewall and having a flange at one end carried in said housing, with said flange having an ear at one side extending through said cover and reshaped thereon to retain the cover on the housing, and a mounting nut having a nipple threadably adjustable in and out of said sleeve and having an enlarged head on the outer end thereof outside said housing.

3. In an electric switch, a one-piece cup-shaped housing having an integral offset at one sidewall thereof, with said offset having an aperture at the end thereof, a cover plate for said housing, and combination means for securing said cover on said housing and mounting said switch comprising an internally threaded flanged sleeve and a mounting nut having an enlarged head and a threaded nipple threadably carried by said sleeve, with said sleeve retained at said flanged portion in said offset portion and extending through said aperture, with the end thereof substantially flush with the outside surface of the wall at the aperture but slightly beyond the same, and with a portion of the flange extending through said cover to be reshaped thereon to retain the cover on the housing, and said mounting nut threadably adjustable in and out of the sleeve to clamp a panel member or the like between the end of the sleeve outside the offset wall and the enlarged head on the mounting nut.

RUDOLF POPP.
